[57] CLAIM

The ornamental design for a tennis racket throatpiece,
as shown.

DESCRIPTION

FIG. 1 is a perspective view of a tennis racket throatpiece showing our new design;

FIG. 2 is a side view of the tennis racket throatpiece;
FIG. 3 is an end view of the tennis racket throatpiece;
FIG. 4 is a partial cross-sectional view taken generally
along the lines 4—4 of FIG. 2 of the tennis racket
throatpiece.
